UNITED STATES PATENT OFFICE.

DAVID L. HILL, OF ROCHESTER, NEW YORK.

SMOKING PIPE.

Application filed July 29, 1922. Serial No. 578,433.

To all whom it may concern:

Be it known that I, DAVID L. HILL, a citizen of the United States, and resident of Rochester, in the county of Monroe and State 5 of New York, have invented certain new and useful Improvements in a Smoking Pipe, of which the following is a specification.

The present invention relates to smoking pipes and an object of the invention is to so 10 connect the mouth piece with the bowl that direct suction from the bottom of the bowl into the mouth of the smoker is impossible, so that the sucking into the mouth of the nicotine and saliva mixture that quickly 15 forms and accumulates in the bowl of an ordinary pipe, while in use, is eliminated. Another object of the invention is to provide a connection between the bowl and the mouth piece which will separate the burning tobacco in the bowl from the saliva, thus enabling the obtaining of a clean dry smoke. 20 Still another object of the invention is to provide a pipe that will be as sanitary as possible, provision being made which will enable 25 the ready cleaning of all portions thereof.

To these and other ends, the invention consists of certain parts and combinations of parts, all of which will be hereinafter described: the novel features being pointed out 30 in the appended claims.

In the drawings:

Fig. 1 is a side view of a pipe constructed in accordance with this invention;

Fig. 2 is a plan view of the pipe; and

Fig. 3 is a vertical section.

Referring more particularly to the drawings, 35 1 indicates the bowl having a short extension 2 with a passageway 9 therein, and 5 indicates the mouth piece having a passageway 10 therein.

Between the mouth piece 5 and the extension 2 of the bowl there is provided a connecting member 3. This connecting member has two longitudinally extending and parallel passageways 7 and 8, one above the other, the passageway 7 being connected to the bowl extension 2 by a screw threaded projection 4 and the passageway 8 being connected to the mouth piece 5 by a screw threaded extension 6, the passageway 7 aligning with the passageway 9 in the bowl extension 2 and the passageway 8 aligning with the passageway 10 in the mouth piece 5. At the inner end of the passageway 7 an externally threaded tube 11^a is arranged with which a cup or cap 11 connects, while at the outer end of the pas-

sageway 8 an externally threaded tube 12^a is provided with which a cup 12 connects. These two cups 11 and 12 may contain absorbent cotton and serve to collect any material from the passageways 7 and 8. The connecting member 3 also has two passageways 13 and 14 connected by passageways 7 and 8, arranged parallel to each other, and at right angles to the passageways 7 and 8, 60 the connecting passageway 14 being nearer to the mouth piece than the connecting passageway 13, which is nearer to the bowl. Aligned with the two passageways 14 and 13 are two externally threaded tubes 13^a and 14^a, 65 which are bevelled at 13^b and 14^b, respectively, so that passageways are provided to two removable cups 15 and 16, secured respectively to the projecting ends of the tubes 13^a and 14^a. In the cups 11, 12, 15 and 16 70 considerable absorbent cotton may be arranged.

In the use of the pipe, the bowl 1 is filled with tobacco in the usual manner and the mouth piece is employed for creating a draft 80 through the bowl as is customary. The saliva from the mouth runs down the passageway 10 and collects in the cups 12, 15 and 16. The smoke from the bowl passes from the passageway 7 to the passageway 8 through 85 the two passageways 13 and 14 and is thus separated from the saliva, thus giving a smoke in which no saliva or condensed matters will enter the mouth piece. To a certain extent the dry smoke from the bowl will 90 take up or absorb some of the moisture in the passageway 10, thus tending still further to maintain such passageway in a dry condition. Should the user of the pipe fail to clean the same, as often as should be necessary, any saliva and condensed matters will tend to collect toward the passageway 13 and even should this fill up, a condition which should not be permitted to occur, the smoke still has the passageway 14 to rely upon without creating a suction on the saliva and condensed matter. Furthermore, any further clogging of the passageway 13 or 14 still leaves the other passageway open for direct draft without drawing the clogged matter 95 into the mouth of the user. There will be a slight deposit of condensed matter in the passageway 7 from the smoke but this is not mixed with the saliva which is confined to the passageway 8. The cleaning of the pipe 100 may be easily effected by removing the cap 11 to clean the passageway 7, the cap 12 to clean 105 110

the passageway 8 and the caps 15 and 16 to clean the passageways 13 and 14, respectively.

What I claim as my invention and desire to secure by Letters Patent is:

1. A smoking pipe comprising a bowl, a mouth piece, and a body connecting said bowl and mouth piece, and provided with two passageways, one of which aligns with the passageway of the bowl and the other of which aligns with the passageway of the mouth piece, said body also having two other passageways connecting the first two named passageways, one of said last named passageways being further removed from the mouth piece than the other.
2. A smoking pipe comprising a bowl, a mouth piece, and a body connecting said bowl and mouth piece and provided with two parallel passageways arranged one above the other, one of said passageways being aligned with the passageway of the bowl and the other of said passageways being aligned with the passageway of the mouth piece, said body

having also two other passageways at right angles to the first two named passageways and connecting said first named passageway, one of said passageways being farther removed from the mouth piece than the other.

3. A smoking pipe comprising a bowl, a mouth piece, a body connecting the bowl and the mouth piece, provided with two parallel passageways, one of which connects at one end with the bowl, and the other of which connects with the mouth piece, and provided with two other parallel passageways arranged at right angles to the first named passageway and connecting the latter, one nearer the mouth piece than the other, a collecting cup at the end of the first named passageway opposite the bowl, a collecting cup at the end of the second named passageway opposite the mouth piece, and collecting cups connecting with the lowermost passageway of the two first mentioned passageways opposite the lower ends of the two second mentioned passageways.

DAVID L. HILL.
